UNITED STATES PATENT OFFICE.

CHARLES A. YOUNG AND SOLOMON W. YOUNG, OF PROVIDENCE, R. I.

IMPROVEMENT IN ROLLS FOR CLOTH-WINDING MACHINES.

Specification forming part of Letters Patent No. **147,541**, dated February 17, 1874; application filed May 29, 1873.

To all whom it may concern:

Be it known that we, CHARLES A. YOUNG and SOLOMON W. YOUNG, of Providence, in the county of Providence and State of Rhode Island, have invented an Improved Paper Roll for Cloth, of which the following is a specification:

Our invention consists in a paper shell or roll for a cloth winding or measuring machine, and intended as a substitute for the wooden rolls now in use, which are defective in many respects, being liable to allow the cloth to slip on the roll, thus causing the index which registers the number of yards to measure incorrectly. Wooden rolls often split, and are thus rendered useless, causing trouble and loss of time. They are heavier, and take up more space, than the paper roll, which is intended to obviate the above difficulties, and is shown in the accompanying drawings, in which—

Figure 1 represents a shell on the mandrel. Fig. 2 is a section through *x y*. Fig. 3 is an end view of the same. Fig. 4 is an end view of the shell.

The shell A is made of a number of thicknesses of wet paper rolled over an iron arbor. About midway between these thicknesses a

cord is inserted, which forms the spline *a*. The whole being pasted or glued together, makes a very hard shell, which, after being dried, is ready to receive the cloth.

The shell, being placed on the mandrel B, is held in position by the spline *a*, which fits in a corresponding groove in the mandrel, the flattened end of which is pivoted at *c* to a projection on the winding-machine, while the other end revolves in a bearing which permits of its being easily removed for the purpose of changing the shell.

Cord is considered the best material for forming the spline; but other substances may be used, as leather, wood, or pasteboard.

The spline may, also, be made of any shape; a semicircular one, however, is more easily adapted to the purpose.

What we claim as our invention is—

In a cloth winding or measuring machine, a paper shell or roll, constructed and secured to the mandrel substantially as and for the purpose herein described.

CHARLES A. YOUNG.
SOLOMON W. YOUNG.
